UNITED STATES PATENT OFFICE.

OTTO W. SCHAUML, OF PHILADELPHIA, PENNSYLVANIA.

DESIGN FOR A SHUTTLE.

SPECIFICATION forming part of Design No. 30,623, dated April 25, 1899.

Application filed March 16, 1899. Serial No. 709,344. Term of patent 14 years.

To all whom it may concern:

Be it known that I, OTTO W. SCHAUML, a citizen of the United States, residing in Philadelphia, in the county of Philadelphia and State of Pennsylvania, have invented a certain new and original Design for Shuttles; and I do hereby declare the following to be a full, clear, and exact description of the invention, such as will enable others skilled in the art to which it applies to make and use the same, reference being had to the accompanying drawings, and to letters of reference marked thereon, which form a part of this specification.

The invention is fully illustrated in the accompanying drawings, wherein four views of a shuttle embodying my design appear.

Figure 1 is a top plan view of the shuttle; Fig. 2, a rear elevation thereof; Fig. 3, an underneath view of said shuttle, and Fig. 4 a sectional view on the line $w-w$ of Fig. 1.

The essential feature of my design consists in the peculiar cross-sectional contour of the shuttle-runner, wherein the rectangular upper or guide groove and the lower or rack-bar groove outlines included in said contour are so disposed that between the guide-groove outline and that portion of said contour which marks the back of the runner there is an intervening space which approximates in width the width of the guide-groove, while the center of the rack-bar-groove outline is in alignment with the side of the guide-groove outline which adjoins said intervening space and wherein the rack-bar-groove outline connects with the outline of a rectangular recess or groove of greater width.

In front or rear elevation the shuttle has its ends tapered quite sharply, as at h . In plan the outline of said shuttle comprises a straight line delineating the back flat surface i of the runner b and a compound-curved line constituting the contour j of the nose g , the extremities of these two lines merging into two short curved lines l and l' , which meet at the apexes of the tapers h , and the continuity of the curved contour of the nose being broken midway by the rectangular outline of an eye-

let j' . The nose g has a somewhat elongated orifice or opening r , three of whose sides are rectangularly disposed, while the fourth one s is curved, being in proximity to and extending almost parallel with the exterior curve of the nose. In cross-section the top surface of the runner appears with a groove a , that is disposed relatively to the upper free or rear edge c of said runner and to an under or rack-bar groove d in said runner that that portion of the top surface of said runner which is situated between the groove a and the edge c and designated in the drawings by the reference character e approximates in width the width of said groove a , and that the rear wall f of said groove a —i. e., the wall thereof which is the farther from the nose g of the shuttle—is situated in a plane which includes the central line of the groove d . Furthermore, the portion c of the top surface and the opposing portion o of the under surface of the runner are disposed in planes which are between those of the portions u and v of said top and under surfaces, respectively, and the under surface of the runner has a widened groove d' , with which groove it communicates. The sectional contour of the nose portion of the shuttle comprises two curved lines k and k' , which meet at their outer ends in a semicircular line q and at their other ends merge into the portions u and v , respectively, of the top and under surfaces of the runner, the inside surfaces appearing as straight parallel lines w and w' .

Having thus fully described my invention, what I claim, and desire to secure by Letters Patent, is—

The design for a shuttle, substantially as herein shown and described.

In testimony that I claim the foregoing I have hereunto set my hand this 13th day of March, 1899.

OTTO W. SCHAUML.
